(57) ABSTRACT

A new *Eucalyptus grandis* tree particularly distinguished by having a fast growth rate, excellent frost tolerance, and good coppicing properties, is disclosed.

5 Drawing Sheets

1

ACKNOWLEDGEMENT OF FEDERAL RESEARCH SUPPORT

The present invention was supported in part by funds from the U.S. Government. The U.S. Government therefore may have certain rights in the invention.

Genus and species: *Eucalyptus grandis*.
Variety denomination: 'G4'.

BACKGROUND OF THE NEW PLANT

The present invention comprises a new and distinct variety of *Eucalyptus*, botanically known as *Eucalyptus grandis*, and hereinafter referred to by the variety name 'G4'. It is characterized by having a fast growth rate, excellent frost tolerance, and good coppicing properties when grown under normal forestry practices in central, southern, and possibly northern Florida.

'G4' originated from a group of 31,725 seedlings of *E. grandis*. 'G4' is the result of open-pollination in a third-generation seedling seed orchard at Palmdale, Fla. The female (seed) parent of 'G4' is the proprietary *E. grandis* seedling selection with the identification number '1480' (unpatented) characterized by its fast growth and average frost tolerance. The male (pollen) parent of 'G4' is unknown. The maternal parent (1480) originated from control-pollination. The female (seed) parent of '1480' is the proprietary *E. grandis* seedling selection with the identification number '1179' (unpatented) characterized by its good growth and acceptable frost tolerance. The male (pollen) parent of '1480' is the proprietary *E. grandis* seedling selection with the identification number '1013' (unpatented) also characterized by its good growth and acceptable frost tolerance. 'G4' was selected as a single clone from the progeny of the above stated open-pollination during February 1982.

'G4' was first asexually propagated in June of 2007 in Lake Alfred, Fla. through cuttings and in vitro propagation. Asexually propagated trees of 'G4' have remained true to the original selected tree, and all characteristics of the tree have been transmitted and retained through three successive asexual vegetative generations.

2

Plant Breeder's Rights for this cultivar have not been applied for. 'G4' has not been made publicly available more than one year prior to the filing of this application.

5 DESCRIPTION OF THE PHOTOGRAPH(S)

This new *eucalyptus* tree is illustrated by the accompanying photographs which show the tree's form and foliage. The colors shown are as true as can be reasonably obtained by conventional photographic procedures. The photographs are of a tree approximately 13-years old.

FIG. 1 shows the overall plant habit including foliage.

FIG. 2 shows a close-up of over-mature leaves and a few seeds.

FIG. 3 shows a close-up of the trunk.

FIG. 4 shows the branches at the top of the tree.

FIG. 5 shows a close-up of the mature seeds.

FIG. 6 shows a close-up of the coppice.

20 DESCRIPTION OF THE NEW CULTIVAR

The following detailed description sets forth the distinctive characteristics of 'G4'. The present botanical description is that of 13-year-old trees growing near Mulberry, Fla. The colors (except those in common terms) are described from R.H.S. Colour Chart published by The Royal Horticultural Society in London (second edition), in association with the Flower Council of Holland.

25 DETAILED BOTANICAL DESCRIPTION

Classification:

Botanical.—*Eucalyptus grandis* var. 'G4'.

Common name.—*Eucalyptus*.

30 Parentage:

Female parent.—'1480' (unpatented).

Male parent.—Unknown.

Tree:

Size.—Height: About 16.0 m. Spread: About 3.0 m.

Vigor.—Good.

Density.—Open.

<i>Form (overall shape of tree).</i> —Narrowly upright with somewhat drooping branches.	<i>Anther filament length.</i> —About 1.0 cm. <i>Pistil number.</i> —1.
<i>Growth habit.</i> —Evergreen.	<i>Pistil length.</i> —Less than 1.0 cm.
<i>Trunk and branches:</i>	<i>Fruit/seed (if produced):</i>
<i>Trunk texture.</i> —Smoother at top.	<i>Size.</i> —Length: 0.5 cm to 0.7 cm. Width: 0.5 cm to 0.8
<i>Trunk bark color.</i> —Mottled grey, pink.	cm.
<i>Branch texture.</i> —Smooth.	<i>Number.</i> —3 to 7 capsules per cluster.
<i>Branch color.</i> —Gray-reddish.	<i>Shape.</i> —Pyriform.
<i>Leaves:</i>	<i>Texture.</i> —Smooth, woody.
<i>Size (lamina average).</i> —Length: 10.0 cm to 15.0 cm.	<i>Apex.</i> —Cuspidate.
<i>Width.</i> —2.0 cm.	<i>Base.</i> —Attenuate.
<i>Type.</i> —Simple, petiolate, alternate, persistent.	<i>Color.</i> —Immature: Green. Mature: Gray brown.
<i>Shape.</i> —Narrow lanceolate, slightly sickle shaped.	<i>Stalk.</i> —Short.
<i>Apex.</i> —Acuminate.	<i>Resistance/tolerance to diseases/pests:</i> No unusual susceptibilities noted.
<i>Base.</i> —Typically acute, can be slightly unequilateral, slightly offcenter midrib.	
<i>Margin.</i> —Smooth, wavy.	COMPARISON WITH PARENTAL AND KNOWN VARIETIES
<i>Surface texture (both surfaces).</i> —Glabrous.	
<i>Color.</i> —Upper surface: Green. Lower surface: Paler green.	
<i>Petiole.</i> —Shape: Slightly flattened with a groove at top.	20 'G4' differs from the female parent '1480' (unpatented) by having faster growth and better frost tolerance than '1480'. In addition, 'G4' had good coppicing properties.
<i>Length.</i> —1.0 cm to 2.0 cm. <i>Width.</i> —0.1 cm to 0.2 cm.	
<i>Color.</i> —Light green and pink. <i>Texture.</i> —Smooth.	There are no commercial varieties known to the inventor which can be compared with 'G4'.
<i>Flowers:</i>	
<i>Type.</i> —Clustered.	
<i>Blossom period.</i> —Mid-September to late-October.	
<i>Fragrance.</i> —Mild.	
<i>Reproductive organs:</i>	
<i>Stamen number.</i> —Many.	
<i>Anther color.</i> —White.	

I claim:

1. A new and distinct variety of *Eucalyptus grandis* tree as shown and described herein.
